C. E. REDDIG

PRIME MOVER DYNAMO PLANT

Filed Nov. 20. 1922

Inventor:
Charles E. Reddig.
by *Pat Ch Palmer* Atty.

UNITED STATES PATENT OFFICE.

CHARLES E. REDDIG, OF KEW GARDENS, NEW YORK, ASSIGNOR TO WESTERN ELECTRIC COMPANY, INCORPORATED, OF NEW YORK, N. Y., A CORPORATION OF NEW YORK.

PRIME MOVER DYNAMO PLANT.

Application filed November 20, 1922. Serial No. 302,926.

To all whom it may concern:

Be it known that I, CHARLES E. REDDIG, a citizen of the United States, residing at Kew Gardens, Richmond Hill, in the county of 5 Queens, State of New York, have invented certain new and useful Improvements in Prime Mover Dynamo Plants, of which the following is a full, clear, concise, and exact description.

10 This invention relates to prime mover dynamo plants, and particularly to such plants employing an internal combustion engine to drive a generator used for charging a storage battery.

15 Its primary object is to regulate automatically the output of the generator so as to secure a tapering charge for the battery.

In accordance with the general features 20 of the invention there are provided means for controlling the power output of the dynamo in accordance with the amount of fuel in the fuel supply tank of the engine, and auxiliary means to overcome the effect of the fuel controlled means when an excess 25 load is inserted in the generator circuit.

The drawing is an elevation partially in section showing one embodiment of the invention.

As shown in the drawing, an internal combustion engine 5 operates a dynamo electric machine 7 having leads 8 and 9 connected to the terminals thereof. A battery 10 and a load 11, such as electric lamps, are inserted across leads 8 and 9. A switch 12 is provided for cutting the load 11 into or out of the circuit. The crank shaft 13 of the engine is geared to a cam shaft 14 upon which an ignition timing mechanism 15 is rotatably mounted. The engine is provided with 30 a fuel tank 16, holding, preferably, an amount of fuel very slightly in excess of that required to completely charge the battery. By the use of this feature a slight overcharge may be secured; but any excessive overcharge is effectually prevented. In the tank is a float 17 attached to a lever 18 pivoted at 19 to one side of the tank. Attached to lever 18 is a vertical bar 20 having at its upper end a horizontal fork 22 between the prongs of which is a pin 23 projecting from the timer 15.

As the level of the fuel in the tank is lowered, the float 17 drops, lowering the lever 18 and the horizontal bar 20 thereby rotating the ignition timer mechanism 15 in a

clockwise direction to retard the spark and reduce the speed of the engine. This reduces the power output of the generator and supplies the desired tapering charge to the battery 10.

If it is desired to connect the load 11 into the circuit during the charging of the storage battery, a load responsive solenoid 25, operating a plunger 26, formed about, or otherwise attached to, bar 20, is inserted into lead 9. Upon the insertion of a load into the circuit, this solenoid will be energized, lifting plunger 26 and bar 20 and rotating the timer 15 in a counter-clockwise direction to overcome any rotation of the timer caused by a drop in the height of the fuel in the tank 16. In this manner the timer may be regulated to adjust the speed of the engine to any sized load.

It will be evident that the ignition timer 75 control means may be replaced by a throttle valve control means and that other changes may be made in the apparatus without departing from the spirit of the invention.

The invention claimed is:

1. In combination, an engine operated by liquid fuel, a fuel supply tank, and means responsive to the amount of fuel in the tank for regulating the speed of the engine.

2. In combination an internal combustion 85 engine, a fuel supply tank therefor, and means responsive to the height of the fuel in the tank for regulating the speed of the engine.

3. In combination, an internal combustion 90 engine, an ignition timing mechanism therefor, a fuel supply tank for the engine, and means responsive to the height of the fuel in said tank for regulating said timing mechanism.

4. In combination, an internal combustion engine, an ignition timing mechanism and a fuel supply tank therefor, means responsive to the height of the fuel in said tank for regulating said timing mechanism, and 95 means for stopping the engine at a predetermined time.

5. In a prime mover dynamo plant, an internal combustion engine, a dynamo electric machine driven thereby, a storage battery 100 to be charged by the dynamo electric machine, a fuel supply tank for the engine, and means responsive to the amount of fuel in the fuel supply tank for securing a tapering charge for the battery and for stopping the 110

2
engine when the battery has been sufficiently charged.

3. In combination an internal combustion engine, a generator driven thereby, a storage battery charged by the generator, a fuel supply tank for the engine to hold substantially enough fuel to charge the storage battery, and means responsive to the height of the fuel in the tank to so regulate the speed of the engine so as to give tapering charge to the battery.

4. In a prime mover dynamo plant, an internal combustion engine, a dynamo electric machine driven thereby, a load circuit for the dynamo electric machine, a storage battery and a variable load connected across said circuit, a fuel supply tank for the engine, means to slowly decrease the speed of the engine as the fuel in the tank is exhausted, and means responsive to said variable load for overcoming the effect of the first mentioned means.

5. In combination an internal combustion engine comprising a cam shaft, a fuel supply tank for the engine, a float in said tank, an ignition timing mechanism rotatively mounted upon said cam shaft, and bar and lever members connecting the float and the timing mechanism so that as the float is lowered the timing mechanism will be rotated about the cam shaft.

6. A storage battery charging system comprising a storage battery, a dynamo electric machine to charge the storage battery, an internal combustion engine to operate the dynamo electric machine, a cam shaft on the engine, an ignition timing mechanism rotatably mounted on the cam shaft, a fuel supply tank to supply to the engine substantially the amount of fuel necessary to charge the storage battery, a float in said tank, and bar and lever members to connect the float with the timing mechanism so that as

7. the float is lowered the timing mechanism will be rotated to retard the spark and reduce the speed of the engine.

8. In a prime mover dynamo plant, an internal combustion engine, speed control means for the engine, a dynamo electric machine driven by the engine, a load circuit for the dynamo electric machine, a storage battery and a variable load connected across said circuit, a fuel supply tank for the engine, a float in said tank, means connected with said float for actuating said speed control means, and electrical means operating in conjunction with the last mentioned means to overcome the effect of the float upon said speed control means.

9. In a prime mover dynamo plant, an internal combustion engine, a dynamo electric machine driven thereby, a load circuit for the dynamo electric machine, a storage battery and a variable load connected across said circuit, a cam shaft on said engine, an ignition timer rotatably mounted on the cam shaft, a fuel supply tank for the engine, a lever in the tank pivoted to one side thereof, a float at the end of said lever, a bar for connecting the lever with the timer so that as the float is lowered the timer will be rotated to retard the spark and reduce the speed of the engine, a portion of said bar being formed of magnetic material, a load responsive solenoid connected in said circuit and formed about said magnetic portion of the bar which acts as a plunger, so that by the energization of the solenoid the effect of the lowering of the fuel in tank will be overcome when an increase in the speed of the engine is necessary to carry the load.

10. In witness whereof, I hereunto subscribe my name this 13th day of November A. D., 1922.

CHARLES E. REDDIG.
